AIR IMPELLER

Richard W. Kritzer, Chicago, Ill.

Application December 22, 1941, Serial No. 423,878

12 Claims. (Cl. 230—137)

The invention relates to air impellers.

One object of the invention is to provide an air-impeller of high capacity or efficiency.

Another object of the invention is to provide an air-impeller of the drum-type in which a belt is guided to form pockets which are increased in area during the rotation of the drum, so as to tend to draw air into the pockets at the intake side of the drum and are reduced in area adjacent the discharge side to tend to expel the air from the pockets.

Other objects of the invention will appear from the detailed description.

The invention consists in the several novel features which are hereinafter set forth and are more particularly defined by claims at the conclusion hereof.

In the drawings: Fig. 1 is a transverse section through an impeller embodying the invention. Fig. 2 is a section taken on line 2—2 of Fig. 1. Fig. 3 is a section similar to Fig. 1 illustrating the impeller in a different rotating position. Fig. 4 is a similar section illustrating the eccentrically mounted belt-guides adjusted for varying the air-flow.

The invention is exemplified in a trunk or casing through which air is forced from an inlet portion to an aligned outlet portion. The casing comprises straight end-walls 19 and side-walls 12. These walls form a duct which is rectangular in cross-section. A rotor of the drum-type is mounted to rotate in the duct to impel air from the inlet portion of the casing through the outlet portion. The rotor comprises heads or end-members 13 adjacent the inner face of the walls 12, respectively. Heads 13 are rigidly connected together for conjoint rotation by rods 19, the ends of which are riveted or suitably secured in the heads 13. One of the heads 13 has affixed thereto a trunnion 14 which is journaled in a bearing 15 which is supported from the casing and the other head 13 has affixed thereto a trunnion 17 which is coaxial with the trunnion 14 and is journaled in a bearing 18 which is fixed to the opposite end-wall 12 of the casing. A belt-pulley 16 is fixed to the outer end of trunnion 14 for driving the drum at the desired speed.

A series of belt-guides, such as rollers 20, extend between and have their ends journaled for rotation on their own axes in the heads 13. The rollers are parallel to the axis of the rotor and form a circumferential series of belt-guides adjacent the outer periphery of the heads 13.

A series of rollers 32 corresponding in number to the series of rollers 20 are parallel to the axis of the rotor and are supported for bodily rotation around an axis which is parallel and eccentric to the axis of the rotor. Rollers 32 are supported in a drum 22 which comprises heads

30 adjacent the inner faces of the heads 13 of the rotor and members 31 which rigidly connect the heads 30. Each roller 32 is journaled for rotation on its own axis in the heads 30. The drum 22 is journaled for rotation on a shaft 23 which is carried by and secured in hangers or arms 24 and trunnions 25, 26 on said arms, respectively, which are supported coaxially with the rotor in the trunnions 14 and 17 on the rotor. 10 By supporting the shaft 23 for the drum 22 on the arms 24, the drum 22 which carries the rollers 32 will be supported for rotation on an axis which is parallel and eccentric to the axis of the rotor. During the operation of the impeller, arms 24 and trunnions 25 and 26 are locked to hold the shaft 23 in its assigned eccentric position by means of an arm 27 which is fixed to trunnion 26 and a screw 28 which locks arm 27 to a disk or flange 29 on the stationary bearing 18. 15 An endless belt 21 extends across the casing between the heads 13 of the rotor and is alternately looped around the rollers 20 which are rotated bodily with the rotor and the rollers 32 which are carried by the drum 22 which is rotatable on an axis which is eccentric to the axis of the rotor. This alternate looping of the belt 21 around the rollers 20 which rotate bodily with the rotor and the rollers 32 which are bodily rotatable on shaft 23 causes the belt to rotate the drum 22 and the rollers 32 carried thereby on the eccentric axis of the drum while the rotor is driven. The drum 22 and rollers 32 during the rotation of the drum are free to rotate on shaft 23 so that the drum 22 will be rotated by the bodily rotation of the belt 21 with the rotor. 20 By looping the belt alternately around guides, such as rollers 20, circumferentially arranged on the rotor, and guides, such as rollers 32 which are free to rotate bodily on an axis eccentric and parallel to the axis of the rotor, the belt, during the rotation, will, at the intake side, successively form an enlarged sector-shaped pocket of great area which will be progressively decreased in area as the loop between two rollers 20 and the intermediate roller 32 forming the pocket passes away from the inlet side of the casing toward the outlet side. Members 31, which are fixed to the heads 30 of the drum 22, 25 guide the loops of the belt around rollers 32 during the rotation of the rotor and the drum 22. While the rotor is driven, the belt itself has a limited reciprocatory movement around the guide-rollers. The belt 21 may be of suitable 30 somewhat elastic material so that it will be kept taut and to take up any slack which results from constantly changing relative position of the rollers 20 and the rollers 32 while the rotor is driven. If desired, flexible, non-elastic material may be used since an intermittent limited amount of

slack in the belt will not interfere with the operation of the impeller. A cut-off plate 33 is fixed in the casing adjacent the inlet side of the rotor. A cut-off plate 34 is fixed in the casing adjacent the discharge side of the rotor.

The operation will be as follows: assuming the rotor to be continuously driven, pulley 16 and heads 13 will be rotated and will bodily move the rollers 20 through a fixed circular path concentric with the axis of the rotor. The drum 22 is free to rotate on the shaft 23. The rollers 32 on drum 22 are confined for rotation in a circular path which is eccentric to the circular path of rollers 20 on the rotor. The rollers 32 are located within the circumferential extent of and between the ends of the rotor. The movement of the rollers 20 and the rotor in the fixed circular path will cause the belt 21 to bodily move the rollers 32 in a fixed eccentric circular path around shaft 23. This will cause the loops between each pair of guide-rollers 20 on the rotor and the intermediate guide rollers 32 on drum 22 to form a sector-shaped pocket of maximum area which will be loaded with air from the inlet side of the rotor during the intake cycle of that loop of the belt, as illustrated by the loop at the top of the rotor in Fig. 1. As the rotor continues in rotation the magnitude of the angle formed by the sides and the depth of each belt-loop and the resultant area of the sector-shaped pocket will be progressively reduced, as illustrated in the pocket at the right-hand side of Fig. 1. As the trailing roller 20 of each loop passes the cut-off 33 this reduction in area will cause the air in the pocket in advance thereof to be compressed. As the leading roller 20 of each loop passes away from the sidewall 19 at the discharge side, the air will be expelled from the loop and impelled into the duct at the discharge side of the rotor until the rotor reaches the position at the lower right-hand side of Fig. 3. When the leading roller 20 of each loop has passed the inner end of the cut-off 34 at the discharge side, the pocket formed in the loop in advance thereof will be of reduced area and commence to load with air from the inlet side of the duct. As the same loop continues in rotation, the area of the pocket will be increased to its maximum, as shown at the top loop of Fig. 1, and this will produce a tendency to draw air into the pocket. In this manner the loops of the belt will form pockets of maximum area in loading and their area will be reduced to compress the air and discharge it from the rotor at the discharge side of the duct.

The axis on which the roller-guides 32 are bodily rotatable relatively to the axis of the rotor may be varied by the adjustment of arms 24 and trunnion 26, as illustrated in Fig. 4. This can be effected by the angular adjustment of arms 24 which are supported in the trunnions 14, 17, through arm 27 and locking it by screw 28 to disk 29, in its adjusted position. When this is done the commencement of the loading of the pockets at the lower left-hand corner is deferred for a longer period and this reduces the volume of the air impelled through the casing. This locking device permits the arms 24 to be adjusted through an arc of 180° or more so that the flow of air may be reversed in the duct without reversing the direction of rotation of the rotor.

The invention exemplifies an air-impeller which is of high capacity, is adapted for use in a straight duct, and can be regulated to vary the volume of air impelled through the duct.

The invention is not to be understood as re-

stricted to the details set forth, since these may be modified within the scope of the appended claims, without departing from the spirit and scope of the invention.

5 Having thus described the invention, what I claim as new and desire to secure by Letters Patent is:

1. In an impeller, the combination of a casing, a rotor in the casing provided with a circumferential series of belt-guides extending parallel to the axis of, and mounted for rotation in a circular path concentric with the axis of the rotor, means for driving the rotor, a second series of belt-guides extending parallel to the rotor-axis, 15 means for supporting the second series of belt-guides located within the circumferential extent of and between the ends of the rotor and for bodily rotation on an axis parallel and eccentric to the axis of the rotor, and a belt alternately looped 20 around the guides on the rotor and the second series of guides and adapted to rotate the second series of guides around the eccentric-axis when the rotor is driven.

2. In an impeller, the combination of a casing, 25 a rotor in the casing provided with a circumferential series of belt-guiding rollers extending parallel to the axis of, and mounted for rotation in a circular path concentric with the axis of the rotor, means for driving the rotor, a series 30 of belt-guides extending parallel to the rotor-axis, means for supporting the belt-guides located within the circumferential extent of and between the ends of the rotor and for bodily rotation on an axis parallel and eccentric to the 35 axis of the rotor, and a belt alternately looped around the rollers on the rotor and the series of guides, and adapted to rotate the series of guides around the eccentric-axis when the rotor is driven.

40 3. In an impeller, the combination of a casing, a rotor in the casing provided with a circumferential series of belt-guides extending parallel to the axis of, and mounted for rotation in a circular path concentric with the rotor, means for 45 driving the rotor, a series of belt-guiding rollers extending parallel to the rotor-axis, means for supporting the rollers located within the circumferential extent of and between the ends of the rotor and for bodily rotation on an axis parallel 50 and eccentric to the axis of the rotor, and a belt alternately looped around the guides on the rotor and the rollers, and adapted to rotate the second series of guides around the eccentric-axis when the rotor is driven.

55 4. In an impeller, the combination of a casing, a rotor in the casing provided with a circumferential series of belt-guiding rollers extending parallel to the axis of, and mounted for rotation in a circular path concentric with the axis of the 60 rotor, means for driving the rotor, a second series of belt-guiding rollers extending parallel to the rotor-axis, means for supporting the second series of rollers located within the circumferential extent of and between the ends of the 65 rotor and for bodily rotation on an axis parallel and eccentric to the axis of the rotor, and a belt alternately looped around the rollers on the rotor and the second series of rollers, and adapted to rotate the second series of rollers around the 70 eccentric-axis when the rotor is driven.

5. In an impeller, the combination of a casing, a rotor in the casing, comprising a pair of heads connected together for conjoint rotation, a circumferential series of belt-guides extending parallel to the axis of, and mounted on the heads

for rotation therewith in a circular path concentric with the axis of the rotor, means for driving the rotor, a drum extending between the heads mounted for rotation on an axis parallel and eccentric to the axis of the rotor, a second series of belt-guides extending parallel to the rotor-axis and mounted on said drum for rotation in a circular path on said eccentric axis, and a belt alternately looped around the guides on the rotor and the guides of the second series and adapted to rotate the second series of guides and said drum around the eccentric axis when the rotor is driven.

6. In an impeller, the combination of a casing, a rotor in the casing comprising a pair of heads connected together for conjoint rotation, trunnions secured to the heads, a circumferential series of belt-guides extending parallel to the axis of, and mounted on the heads for rotation therewith in a circular path concentric with the axis of the rotor, means for driving the rotor, a drum extending between the heads mounted for rotation on an axis parallel and eccentric to the axis of the rotor, a second series of belt-guides extending parallel to the rotor-axis and mounted for rotation in a circular path on said eccentric axis, and a belt alternately looped around the guides on the rotor and the guides of the second series and adapted to rotate the second series of guides and said drum around the eccentric axis when the rotor is driven.

7. In an impeller, the combination of a casing, a rotor in the casing comprising a pair of heads connected together for conjoint rotation, a circumferential series of belt-guiding rollers extending parallel to the axis of, and extending between and mounted in the heads for bodily rotation therewith in a circular path concentric with the rotor, a drum extending between the heads mounted for rotation on an axis parallel and eccentric to the axis of the rotor, means for driving the rotor, a second series of belt-guides extending parallel to the rotor-axis and mounted on said drum for rotation in a circular path on said eccentric axis, and a belt alternately looped around the guides on the rotor and the guides of the second series and adapted to rotate the drum and the second series of guides around the eccentric axis when the rotor is driven.

8. In an impeller, the combination of a casing, a rotor in the casing comprising a pair of heads connected together for conjoint rotation, a circumferential series of rollers extending parallel to the axis of, and mounted on the heads for rotation in a circular path on an axis concentric with the rotor, a drum extending between the heads mounted for rotation on an axis parallel and eccentric to the axis of the rotor, means for driving the rotor, a second series of rollers extending parallel to the rotor-axis and mounted on the drum for rotation on the eccentric axis, and a belt alternately looped around the rollers on the rotor and on the drum and adapted to rotate the drum and rollers thereon around the eccentric axis when the rotor is driven.

9. In an air-impeller, the combination of a casing, a rotor in the casing comprising a pair of heads connected together for conjoint rotation, trunnions on the outer sides of said heads, a circumferential series of belt-guides extending parallel to the axis of, and extending between and mounted on, the heads for rotation therewith in a circular path concentric with the axis of the rotor, means for driving the rotor, rotatable

means extending between the heads, a shaft for rotatably supporting said means, arms for supporting said shaft from the trunnions eccentrically to the axis of the rotor, a second series of belt-guides extending parallel to the rotor-axis and mounted on said means for rotation in a circular path on the eccentric axis, and a belt alternately looped around the guides on the rotor and the guides of the second series and adapted to rotate the second series of guides and said rotatable means around the eccentric axis when the rotor is driven.

10. In an air-impeller, the combination of a casing, a rotor in the casing comprising a pair of heads connected together for conjoint rotation, trunnions on the outer sides of said heads, a circumferential series of belt-guides extending parallel to the axis of, and extending between and mounted on, the heads for rotation therewith in a circular path concentric with the axis of the rotor, means for driving the rotor, a drum extending between the heads, a shaft for rotatably supporting said drum, arms for supporting said shaft from the trunnions eccentrically to the axis of the rotor, a second series of belt-guides extending parallel to the rotor-axis and mounted on said drum for rotation in a circular path on the eccentric axis, and a belt alternately looped around the guides on the rotor and the guides of the second series and adapted to rotate the guides and said means around the axis when the rotor is driven.

11. In an air-impeller, the combination of a casing, a rotor in the casing provided with a circumferential series of belt-guides extending parallel to the axis of, and mounted for rotation with, the rotor, a second series of belt-guides extending parallel to the rotor axis, means for supporting the second series of belt-guides located within the circumferential extent of and between the ends of the rotor and for rotation in a circular path on an axis parallel and eccentric to the axis of the rotor, means for driving the rotor, a belt alternately looped around the guides on the rotor and the second series of guides and adapted to rotate the second series of guides around the eccentric axis by the rotation of the rotor, and means for adjusting the supporting means to vary the circumferential position of the eccentric axis around which the second series of guides rotates.

12. In an air-impeller, the combination of a casing, a rotor in the casing comprising a pair of heads connected together for conjoint rotation, trunnions on the outer sides of said heads, a circumferential series of belt-guides extending parallel to the axis of, and extending between and mounted on, the heads for rotation therewith in a circular path concentric with the axis of the rotor, means for driving the rotor, a drum extending between the heads, a shaft for rotatably supporting said drum, arms for supporting said shaft from the trunnions eccentrically to the axis of the rotor, a second series of belt-guides extending parallel to the rotor-axis and mounted on said drum for rotation in a circular path on the eccentric axis, a belt alternately looped around the guides on the rotor and the guides on the drum and adapted to rotate the guides and said means around the axis when the rotor is driven, and means for adjusting the position of the drum in the rotor.
